Specification for Design.

Patented Apr. 16, 1918.

Application filed January 17, 1918. Serial No. 212,355. Term of patent 14 years.

To all whom it may concern:

Be it known that I, WILLIAM A. STEVENS, a citizen of the United States, and a resident of San Francisco, in the county of San Francisco and State of California, have invented a new, original, and ornamental Design for a Non-Skid Tire, of which the following is a specification, reference being had to the accompanying drawing, forming part thereof.

In the drawing:

Figure 1 is a perspective view of a tire showing the ornamental design.

Fig. 2 is an enlarged plan view of one

complete series of the projections upon the surface of the tire.

What I claim is:—

The new and ornamental design for a non-skid tire, substantially as shown.

In testimony whereof, I have hereunto set my hand this fourth day of January 1918, in the presence of the two subscribed witnesses.

WILLIAM A. STEVENS.

Witnesses:

G. L. MEADE,

ELIZABETH S. BARR.
